LOCK STITCH SEWING MACHINE

Norman V. Christensen, Chicago, and George Sauer, Berwyn, Ill., assignors to Union Special Machine Company, Chicago, Ill., a corporation of Illinois

Application December 9, 1935, Serial No. 53,553

15 Claims. (Cl. 112—181)

This invention relates to sewing machine, particularly of the lock stitch type wherein a loop taker or rotary hook cooperates with the needle to form seams in fabric progressively advanced by a feed element.

The general aim of our invention is to simplify and otherwise structurally improve sewing machines of the specific type referred to with a view toward reducing friction and vibration to a minimum and toward facilitating lubrication from a storage supply of oil so that the machines can be run at much higher speeds than heretofore without overheating and excessive wear of the parts, and without attention other than required for the replenishment of the oil supply at protracted intervals.

The foregoing advantages we attain in practice, as hereinafter more fully disclosed, by providing a feed actuating shaft in the form of a sleeve 20 around the rotary hook shaft, and driving the sleeve and the rotary hook shaft from the main shaft of the machine, through a transmission enclosed for splash lubrication in a single sealed housing containing a supply of lubricating oil, 25 all of the aforesaid shafts, as well as a feed regulating shaft entering the housing through suitable bearings in the side wall of said housing; and by actuating the feed element from a pair of eccentrics on the feed shaft directly at opposite 30 sides of a bearing for said feed shaft, one of said eccentrics being coordinated with the feed element through a rock shaft to impart feed movements to said element and the other eccentric being direct-connected to the feed element to impart the necessary lift movements thereto.

Other objects and attendant advantages will appear from the detailed description which follows of the attached drawings, wherein Fig. I is a side elevation of a lock stitch sewing machine conveniently embodying our invention, a portion of the hollow frame of the machine being broken out to expose certain of the mechanism at the interior.

Fig. II is a plan sectional view taken as indicated by the arrows II—II in Fig. I with a portion of the work support or bed plate of the machine broken away and sectioned to show underlying parts.

Fig. III is a transverse sectional view of the machine taken as indicated by the arrows III—III in Figs. I and II.

Fig. IV is a fragmentary transverse staggered sectional view taken as indicated by the arrows IV—IV in Fig. II; and

Fig. V is a fragmentary transverse sectional view taken as indicated by the arrows V—V in Fig. II.

The sewing machine herein illustrated comprises a bed plate or work support 1, with a hollow standard 2 rising therefrom at one end, said standard having integrally formed therewith a hollow horizontal arm 3 which overreaches the bed plate, and which terminates in a head 4. Guided for vertical reciprocation in the head 4 is a needle bar 5 carrying the usual seaming needle 6, and a presser bar (not shown) to the lower end of which the presser foot 7 is secured. Journaled in suitable bearings within the hollow arm 3 is the main shaft 8 of the machine, to the outer end 10 of which is affixed a combined hand and belt wheel 9 for convenience of manual or power operation. The usual needle thread take-up 10 operates through a vertical slot 11 in the side of the head 4, and is actuated by suitable means on the main shaft 8 from which is also derived the movement for actuating the needle bar 5 in a well-known manner.

From Figs. I and III—V it will be noted that the hollow standard is extended as at 12 below the bed plate 1, and is closed at the bottom by a cover plate for service in accordance with our invention, as a sump or reservoir for lubricating oil. Extending longitudinally below the bed plate is a long shaft 14 which, at its outer or left hand end (Figs. I and II) carries a loop taker or rotary hook 15 preferably of the construction disclosed in application Serial No. 753,671, filed November 19, 1934 by C. O. Nelson. Surrounding the rotary hook shaft 14 is a substantially co-extensive sleeve 16 which, as will be understood from further explanation hereinafter, constitutes the feed shaft of the machine. The shaft 14 and coaxial sleeve 16 extend into the pendant extension 12 of the hollow standard 2 through a bearing boss 17 formed in the end wall 18 of said extension. Adjacent its outer end near the rotary hook the sleeve 16 is journaled in a small bearing lug 19 pendant from the work support.

Disposed above the rotary hook 15 is the feed dog 20 of which the fabric-engaging teeth move up and down, as well as horizontally back and forth in suitable openings of the throat plate 21 of the machine, see Fig. IV. As shown in Figs. II and IV the feed dog 20 is secured, with capacity for vertical adjustment, to a feed bar 22 by means of a screw 23. At the rear end, the feed bar 22 is connected to a pin 24 whereof the ends are engaged in spaced bosses of a yoked rocker 25 secured to a shaft 26 whereof the ends

are in turn journaled in spaced bearing lugs 27 pendant from the work support 1. Pivotaly connected to the rocker 25 at 28, is a telescopic eccentric rod 29 having a strap section 29a which 5 engages an eccentric 30 which, in accordance with our invention, is secured to the sleeve 16 directly to the right of the bearing 19. Affixed to the sleeve 16 directly to the left of the bearing 19 (Fig. II) is another eccentric 31 whereof the 10 strap rod 32 (Fig. IV) is directly connected at 33 to a downwardly and forwardly curved arm 34 of the feed bar 22, see Fig. IV. Thus, under the 15 action of the eccentrics 30 and 31 and the co-ordinated mechanism just described, the required feed and lift movements are imparted to the feed dog 22.

Within the hollow of the standard 2, the hook shaft 14 and the coaxial sleeve 16 are interconnected with the main shaft 8 of the machine by a 20 transmission comprising a group of spur gears 35, 36, 37, 38, 39 and 40. The gears 35-38 are all of the same size and arranged as a train, the lowermost one 35 being secured to the sleeve 16 by a set screw 41, and the uppermost one 38 to the 25 main shaft by a set screw 42. The intermediate or idler gears 36 and 37 are free to revolve between fixed collars 43 and 44 respectively on shafts 45 and 46 supported crosswise of the hollow of the standard 2. The types of needle 30 thread take-up 10 and rotary hook 15 employed in the machine necessitate rotation of the main shaft 8 in the direction of the arrow in Fig. III, and the sleeve 16 in the opposite direction as also indicated by the arrow in Fig. III and thus entails 35 the use of the two intervening idler gears 36 and 37. In other machines where the above described condition does not obtain, a single idler may be substituted in place of the two idlers 36 and 37. As shown in Fig. I the right hand end 40 of the rotary hook shaft 14 extends beyond the gear 35 and has affixed to it the gear 39 which meshes with the gear wheel 40, the latter being formed integral with or secured to the gear wheel 36. The ratio of the gear wheels 39, 40 is, in this 45 instance, one to two, so that the rotary hook shaft 14 is caused to rotate twice for each rotation of the sleeve 16 in the same direction as the latter. It is, however, to be understood that when required for greater or lesser relative speeds of the 50 rotary hook shaft, the ratio between the gears 39 and 40 can be changed, as required.

Our machine is also provided with an improved and simplified feed regulating mechanism which 55 includes a shaft 47 in parallelism with the rotary hook shaft 14 and the sleeve 16 below the work support 1. The right hand end of the regulating shaft 47 (Fig. II) extends through a bearing opening 48 in the front wall of the pendant extension 12 of the standard 2 into the hollow of 60 the latter and has secured to it a finger 49. A torsion spring 50 with one end thereof engaging a fixed lug 51 within the hollow of the standard 2 and with the other end thereof bearing against a lateral projection 49a of the finger 49, tends to 65 rotate the regulating shaft 47 in the direction of the arrow in Fig. III to yieldingly maintain said finger in engagement with the rounded inner end of an adjusting screw 52. As shown, the adjusting screw 52 has threaded engagement with the lug 51 and extends upwardly at an angle through a bearing boss 53 in the side wall 54 of the standard 2 to the exterior where it is provided with a manipulating finger knob 55. Near its left hand 70 end (Fig. II) the regulating shaft 47 is supported in a bearing lug 56 pendant from the work sup-

port. Pivotaly connected at 57 to the end of an arm 58 on the regulating shaft 47 beyond the bearing 56 is a lazy bar or link 59 which is in turn connected at 60 to the tubular section 29b of the telescopic eccentric strap rod 29.

Except for the arrangement of the eccentrics 30 and 31, and the adjusting means for the regulating shaft, the illustrated feed mechanism is generally similar in construction and operation to that featured in U. S. Patent 2,035,508 granted 10 on March 31, 1936, to George Sauer, one of the present applicants jointly with Clarence C. Smith.

From the foregoing, it will be apparent that the sewing machine of the present invention is simple in construction by virtue of the coaxial arrangement of the rotary hook shaft 14 and the feed actuating sleeve 16. Due to placement of the feed and lift eccentrics 30 and 31 directly at opposite sides of the far bearing 19 for the sleeve 16 and by direct connection of the lift eccentric strap 20 to the feed bar 22, the action of the eccentrics is balanced and the operation of the feed mechanism as a whole rendered quieter and smoother. In our machine, the sleeve 16 is rotated at half the speed of the rotary hook shaft 14 in the same direction, from which it follows that the relative surface speed of said shaft in its bearing is only half the surface speed which it would have in a stationary bearing or bearings. Obviously, this results in less friction and wear, the wear being 30 uniformly distributed between the sleeve 16 (which is internally eased for the greater part of its length as shown in dotted lines in Fig. II), the relatively short contacting portions of the shaft 14, and the surfaces of the relatively small 35 relatively spaced bearings 17 and 19 for said sleeve. During operation of the machine, the transmission gears carry up oil from the supply maintained in the reservoir 12 at the bottom of the closed housing constituted by the hollow standard 2, and splash the oil about so that not only are they themselves adequately lubricated at all times, but the bearings for the several shafts as well, part of the splashed oil also finding its way 40 between the rotary hook shaft 14 and the sleeve 16. The machine can thus be safely operated at high speeds in the production of upwards of 5000 stitches per minute without overheating or incurring excessive wear, and without requiring attention except at very infrequent intervals to renew 50 or replenish the oil in the reservoir 12.

Having thus described our invention, we claim:

1. In a lock stitch sewing machine, a rotary hook; a feed element; a main shaft; a pair of coaxial auxiliary shafts respectively carrying the 55 rotary hook and means for actuating the feed element; a closed oil housing into which all three shafts extend; and a transmission interconnecting the three shafts within the housing, said transmission, said shafts and the bearings for 60 the latter being lubricated by the oil in the housing.

2. In a lock stitch sewing machine, a rotary hook; a feed element; a main shaft, a shaft for the rotary hook; a shaft in the form of a sleeve 65 surrounding the rotary hook shaft and carrying means for actuating the feed element; a closed oil housing into which all three shafts extend; and a transmission interconnecting the three shafts within the housing, said transmission, said 70 shafts and the bearings for the latter being lubricated by the oil in the housing.

3. In a lock stitch sewing machine, a rotary hook; a feed element; a main shaft; a parallel shaft for the rotary hook; a shaft in the form of 75

5 a sleeve surrounding the rotary hook shaft and carrying means for actuating the feed element; a closed oil housing into which all three shafts extend; and a group of intermeshing gear wheels interconnecting the three shafts within the housing, said gears, said shafts and the bearings for them being lubricated by the oil in the housing.

4. In a lock stitch sewing machine, a rotary hook; a feed element; a main shaft; a parallel shaft for the rotary hook; a shaft in the form of a sleeve surrounding the rotary hook shaft and carrying means for actuating the feed element; a closed oil housing into which all three shafts extend; and a group of intermeshing gear wheels 10 interconnecting the three shafts within the housing, the ratios of the gear wheels being such that the rotary hook shaft is driven at a higher speed than the sleeve in the same direction.

5. In a lock stitch sewing machine, a rotary hook; a feed element; a main shaft; a parallel shaft for the rotary hook; a shaft in the form of a sleeve surrounding the rotary hook shaft and carrying means for actuating the feed element; a closed oil housing into which all three shafts extend; and a group of intermeshing gear wheels 20 interconnecting the three shafts within the lubricant housing, the ratios of the gear wheels being such that the rotary hook shaft is driven at twice the speed of the sleeve in the same direction.

30 6. In a lock stitch sewing machine, a rotary hook; a feed element; a main shaft; a parallel shaft for the rotary hook; a shaft in the form of a sleeve surrounding the rotary hook shaft and carrying means for actuating the feed element; a closed oil housing into which all three shafts extend; and a group of intermeshing gear wheels 35 interconnecting the three shafts within the housing, the ratios of the gear wheels being such that the sleeve is driven in unison with the main shaft, and the rotary hook shaft driven at a higher speed in the same direction as the sleeve.

7. In a lock stitch sewing machine, a work support; a hollow standard with a horizontal arm overreaching the work support, said standard 45 having an extension below the work support and being closed at the bottom to serve as a reservoir for oil; a main shaft journaled in the horizontal arm; a rotary hook; a feed element; co-axial shafts below the work support respectively carrying the rotary hook, and means for actuating the feed element, said shafts extending through a bearing into the downward extension of the standard; and a transmission 50 interconnecting the main shaft, the rotary hook shaft, and the feed actuating shaft within the hollow of the standard.

8. In a lock stitch sewing machine, a work support; a hollow standard with a horizontal arm overreaching the work support, said standard 60 having an extension below the work support and being closed at the bottom to serve as a reservoir for oil; a main shaft journaled in the horizontal arm; a rotary hook; a feed element; a shaft below the work support carrying the rotary hook; a sleeve surrounding the rotary hook shaft and carrying means for actuating the feed element, said rotary hook shaft and sleeve extending through a bearing into the downward extension of the standard; and a transmission 65 interconnecting the main shaft, the rotary hook shaft and the sleeve within the hollow of the standard.

70 9. In a lock stitch sewing machine, a rotary hook; a feed element; a main shaft; a pair of

auxiliary shafts respectively carrying the rotary hook, and means for actuating the feed element; a feed regulating shaft; a closed oil housing into which all four shafts extend; a transmission interconnecting the main shaft, the rotary hook shaft and the feed actuating shaft within the housing; and means extending to the exterior of the housing for adjusting the feed regulating shaft.

10. In a lock stitch sewing machine, a work support; a hollow standard with a horizontal arm overreaching the work support, said standard having an extension below the work support and being closed at the bottom to serve as a reservoir for oil; a main shaft journaled in the horizontal arm; 15 a rotary hook; a feed element; a shaft below the work support carrying the rotary hook; a sleeve surrounding the rotary hook shaft and carrying means for actuating the feed element; a feed regulating shaft also below the work support 20 and extending through a bearing into the downward extension of the standard; a transmission interconnecting the main shaft, the rotary hook shaft and the sleeve within the standard; and feed regulating shaft adjusting means accessible 25 above the work plate and extending into the hollow of the standard.

11. In a lock stitch sewing machine, a rotary hook; a feed bar; a rotary hook shaft; and a coaxial feed actuating shaft with two eccentrics 30 thereon, one of said eccentrics being connected to the feed bar through a rock shaft to impart feed movements to said bar, and the other eccentric being direct-connected to the feed bar to impart lift movements thereto. 35

12. In a lock stitch sewing machine, a rotary hook; a feed bar; a rotary hook shaft; a co-axial feed actuating shaft with two eccentrics thereon; and straps surrounding said eccentrics, one of said straps being connected to the feed 40 bar through a rock shaft to impart feed movements to said feed bar, and the other of said straps being direct-connected to the feed bar to impart lift movements thereto.

13. In a lock stitch sewing machine, a rotary 45 hook; a feed bar; a rotary hook shaft; a co-axial feed actuating shaft supported near opposite ends thereof in remotely spaced bearings; and a pair of eccentrics on said shaft directly at opposite sides of one of the bearings, one of said 50 eccentrics being connected to the feed bar through a rock shaft to impart feed movements to said bar, and the other eccentric being direct-connected to the feed bar to impart lift movements thereto. 55

14. In a lock stitch sewing machine, a needle; a cooperating rotary hook; a needle actuating shaft; a feed element; a pair of coaxial auxiliary shafts respectively carrying the rotary hook and means for actuating the feed element; and 60 transmission means coordinating said shafts with one of them serving as a power shaft from which the others are driven.

15. In a lock stitch sewing machine, a rotary hook; a feed bar; a rotary hook shaft; and a co-axial feed-actuating shaft with two eccentrics 65 thereon, one of said eccentrics serving to impart feed movements to the feed bar, and the other eccentric serving to impart lift movements to said bar. 70

NORMAN V. CHRISTENSEN.
GEORGE SAUER.
